SASH HINGE

Clyde W. Kelly, Detroit, Mich., assignor to Detroit Steel Products Company, Detroit, Mich., a corporation of Michigan

Application July 25, 1949, Serial No. 4,113

Term of patent 14 years

(Cl. D10—9)

To all whom it may concern:

Be it known that I, Clyde W. Kelly, a citizen of the United States of America, residing at Detroit, Wayne County, Michigan, have invented a new, original, and ornamental Design for Sash Hinge, of which the following is a specification, reference being had therein to the accompanying drawing, forming a part thereof, wherein:

Figure 1 is a front elevational view of a sash hinge;

Figure 2 is a side view thereof; and

Figure 3 is an end view thereof showing my new design.

I claim:

The ornamental design for sash hinge, substantially as shown.

CLYDE W. KELLY.
